UNITED STATES PATENT OFFICE.

JOHN H. FREY AND JOHN N. KAISER, OF ERIE, PENNSYLVANIA.

BORING HEAD.

Application filed August 29, 1921. Serial No. 496,776.

To all whom it may concern:

Be it known that we, JOHN H. FREY and JOHN N. KAISER, citizens of the United States, residing at Erie, in the county of Erie and 5 State of Pennsylvania, have invented new and useful Improvements in Boring Heads, of which the following is a specification.

This invention relates to adjustable boring tool holders, wherein the component parts 10 are held fixed relatively in a given position through the instrumentality of a lock nut, which when loosened allows the tool holder to be accurately and minutely adjusted with a view of centering or decentering the tool 15 without the use of keys, wrenches or other analogous implements.

The nature and advantages of the invention will be better understood when the following detailed description is read in connection with the accompanying drawings, the invention residing in the construction, combination, and arrangement of parts as 20 claimed.

In the drawings forming part of this application, like numerals of reference indicate similar parts in the several views and wherein:—

Figure 1 is a view in elevation of the tool holder constructed in accordance with the 30 present invention.

Figure 2 is a vertical sectional view therethrough.

Figure 3 is a similar view, showing the tool holder by dotted lines in one of its adjusted positions.

Figure 4 is a top plan view of Figure 3.

Figure 5 is a detail view of the clamping ring.

Figure 6 is a detail view of the tool holder.

Figure 7 is a top plan view of the adjustable ring.

Figure 8 is a transverse sectional view taken on line 8—8 of Figure 7.

Figure 9 is a top plan view of the grooved plate.

Figure 10 is a sectional view taken on line 10—10 of Figure 9.

Figure 11 is a plan view of the tool holder.

The device forming the subject matter of 50 the present invention comprises a tubular casing 10 which is open at one end, and which receives the component parts of the device as illustrated. Arranged within the casing 10 is a clamping ring 11 formed with an inwardly directed flange 12, which flange 55 reposes upon the shoulder 13 of the adjust-

ing ring 14 clearly illustrated in Figures 7 and 8. This adjusting ring is provided with an oblong slot or opening 15 which receives the tubular portion 16 of the tool holder clearly shown in Figure 6. The tool holder is provided with a head 17 and a squared reduced portion 18, the latter being slidably fitted in the squared recess 19 formed on the underside of the adjusting ring 14 and extending across the entire face thereof. The head 17 of the tool holder engages the bottom face of the adjusting ring 14 as clearly illustrated in Figures 2 and 3. The tubular portion of the tool holder is equipped with retaining screws or other suitable fastening elements 20 which are utilized to hold the tool (not shown) positioned within the tool holder.

The lower end of the casing 10 is closed 75 by the plate 21 formed integral therewith as shown in Figures 9 and 10. The upper face of this plate 21 which is arranged beneath the tool holder is formed with spiral grooves 22, and has openings arranged at 80 intervals beyond the grooves for a purpose to be hereinafter referred to. This plate is provided with a depending threaded boss 23 as clearly illustrated in Figure 10, and threaded on this boss is a lock nut 24. The 85 lock nut is provided with a threaded central opening for this purpose, and also formed with an annular flange 25 which embraces the adjacent end of the cylindrical casing 10. Interposed between the lock nut 24 and the 90 adjacent side or face of the plate 21 is a washer, the latter including inner and outer concentrically disposed sections 26 and 27 respectively. These sections are formed with overlapped flanges 28. The clamping 95 ring is provided with threaded bores 29 to receive the threaded screws or other suitable fastening elements 30 which project from the outer section of the washer and through rings 30' which are mounted in 100 openings in the plate 21. These fastening elements 30 hold the parts operatively associated, while the lock nut holds the parts fixed relatively in a set position, it being apparent that when the lock nut is tightened 105 the grooved side of the plate 21 is impinged against the head of the tool holder.

Closing the upper end of the casing 10 is an annulus 31 of U-shaped formation in cross section, the depending portion of 110 which is graduated as at 32 so that the degree of adjustment of the tool holder may

be readily determined. This depending portion of the annulus is also knurled so that it may be properly held incident to the adjustment of the tool holder, it being, of course, understood that the annulus 31 is utilized to effect an adjustment of said holder. The annulus 31 for this purpose is secured to the adjusting ring 14 by means of suitable fastening elements 33. A dust cap of usual construction is indicated at 34 and surrounds the tool holder reposing upon the annulus 31. A spring pressed dog 35 is carried by the tool holder projecting from the head 17 thereof and held positioned within the grooves 22 of the plate 21. This spring pressed dog is adapted, upon rotation of the adjusting ring and the tool holder therewith, to be moved around the spiral groove in the plate 21 thus regulating the sliding movement of the tool holder in the slot 15. This construction provides a guiding means for the movement of the tool holder which is always in position, not liable to encounter any great resistance which would render the device hard of movement, and which renders the desired adjustment in an accurate and efficient manner.

In practice, the tool holder 16 can be quickly and conveniently adjusted to center or decenter the tool with relation to the vertical axis of the device in its entirety, without the use of keys, wrenches or other analogous tools. To accomplish this, it is only necessary to loosen the lock nut 24 which allows the adjusting ring 14 to be rotated within the clamping ring 11, and rotary movement is imparted to the ring 14 through the instrumentality of the annulus 31. As above stated, this annulus is graduated so that the degree of adjustment may be readily determined. By reason of the fact that the adjusting ring is formed with a squared recess 19 to receive the squared portion 18 of the tool holder, the latter is rotated simultaneously with the rotation of the adjusting ring 14. Consequently, the spring pressed dog carried by the tool holder is moved within the grooves 22 of the plate 21, thus causing the tool holder to be shifted through the elongated slot 15 of the ring 14, the desired distance to either side of the center of the ring, depending upon the direction in which the annulus 31 is turned. Subsequent to this adjustment of the tool holder, with a view of either centering or decentering the latter, the lock nut 24 is tightened to hold the parts fixed relatively in a set position, and preventing any movement of the

parts when the tool is under a heavy cut or strain. The lock nut if desired may be equipped with a locking screw 36 which associates the lock nut with the inner section of the washer above described.

While it is believed that from the foregoing description the nature and advantages of the invention will be readily apparent, we desire to have it understood that we do not limit ourselves to what is herein shown and described, and that such changes may be resorted to when desired as fall within the scope of what is claimed.

What we claim is:—

1. An adjustable tool holder comprising a cylindrical casing, a ring arranged within said casing for rotation and having an elongated slot, a tool holder passed through said slot, means for associating the tool holder with the ring for rotation therewith, a plate arranged within the casing and having a spiral groove, a spring pressed dog carried by the tool holder and movable within said groove, whereby said tool holder is moved within said slot and across the ring in either direction incident to the rotation of the ring, and means for locking said parts fixed relatively in a set position. 75 80 85 90 95 100 105 110

2. In a boring head and adjustable tool holder comprising in combination, a tubular casing, a clamping ring provided with an inwardly extending flange arranged within said casing, an adjusting ring rotatably mounted within said casing provided with a reduced shoulder receiving said flange and having an elongated slot, a tool holder mounted thru said slot, a head on said tool holder, a reduced portion on said head mounted in the slot of the adjusting ring for rotation therewith and having sliding movement therein, a spring pressed dog mounted in the head of the tool holder, a plate provided with a threaded shank and having a spirally grooved face engaged by the end of said dog, an annulus mounted on top of the casing and connected with the adjusting ring adapted to regulate transverse movement of the tool holder by rotation of the spring pressed dog in the spiral groove of said plate, and a lock nut mounted on said threaded shank and engaging the outer face of the casing and the bottom of said plate holding the parts in set position.

In testimony whereof we affix our signatures.

JOHN H. FREY.
JOHN N. KAISER,
